Des. 186,527
Patented Nov. 3, 1959

186,527

TOY CULVERT UNLOADER AND STATION

Moses Zion, Brooklyn, N.Y., assignor to The Lionel Corporation, New York, N.Y., a corporation of New York

Application July 9, 1958, Serial No. 51,706

Term of patent 14 years

(Cl. D34—15)

Fig. 1.

Fig. 2.

Fig. 1 is a perspective view of a toy culvert unloader and station showing the new design;

Fig. 2 is a left end elevational view thereof;

Fig. 3 is a top plan view thereof; and

Fig. 4 is a rear view thereof.

I claim:

The ornamental design for a toy culvert unloader and station, as shown.
